(57) **CLAIM**

The ornamental design for a flapper for the roof of a power conditioning subsystem, as shown and described.

DESCRIPTION

FIG. 1 is a perspective view of a flapper for the roof of a power conditioning subsystem showing our new design,
FIG. 2 is a front elevational view thereof,
FIG. 3 is a rear elevational view thereof,
FIG. 4 is a top plan view thereof,
FIG. 5 is a bottom plan view thereof,
FIG. 6 is a left side elevational view thereof,
FIG. 7 is a right side elevational view thereof,
FIG. 8 is a perspective view in a position of use thereof; and,
FIG. 9 is a perspective view in an open position of use thereof.
